UNITED STATES PATENT OFFICE.

JOHN JAMES IRVIN, OF BELLWOOD, PENNSYLVANIA.

DUMP-CAR.

1,121,505.

Specification of Letters Patent. Patented Dec. 15, 1914.

Application filed December 21, 1910. Serial No. 598,489.

To all whom it may concern:

Be it known that I, JOHN JAMES IRVIN, a citizen of the United States, residing at Bellwood, in the county of Blair and State of Pennsylvania, have invented new and useful Improvements in Dump-Cars, of which the following is a specification.

This invention relates to dump cars and more particularly to that type which have displaceable sides.

One of the principal objects of the invention is the provision of means for automatically displacing either one of the sides and for automatically retaining or rerighting the car after the load is dumped.

A further object of the invention is the provision of means for elevating one of the sides as the car is dumped in that direction and for supporting the side in position to be properly engaged with its support, together with means actuated by the side for automatically rerighting the car after the load is dumped and for guiding the body into intimate contact with the body of the car.

Further objects of the invention will appear as the following specific description is read in connection with the accompanying drawings which form a part of this application, and in which:

Figure 1 is a side elevation. Fig. 2 is an end elevation showing the body of the car in upright position. Fig. 3 is a similar view showing it in dumping position. Fig. 4 is a section on line 4-4 of Fig. 1 looking in direction indicated by arrow.

Referring more particularly to the drawing 1 represents a truck of any suitable type which is provided with a central pivoting sill 2 having upstanding pivoting ears 3 which are connected by means of the pivotal bolt 4 with similar ears 5 carried upon a central pivoting sill 6 secured to the floor 7 of the car body.

The car body comprises the floor 7, the end members 8, and the movable sides 9 which latter members have their lower ends guided into closing position with the ends and body by means of reinforcing brackets 10 which are inturned at their ends so as to provide a cam surface 11 adapted to engage the outwardly projecting fingers 12 carried by the floor. The sides are also provided with connecting strips 13 having projecting lower ends 14 adapted to engage apertured

brackets 15 carried by the bottom. Bracing rods 16 are also provided which are bridged between the brackets 10 and a central rib 17.

Pivoted at one end in brackets 18 carried by the ends 8 are raising levers 19 whose opposite ends are pivotally connected in brackets 20 carried upon the ends of the sides adjacent their upper edges and carry suitable bracing arms 21 which limit the downward movement of the sides when in raised position as shown in Fig. 3. These levers have adjustably connected thereto adjacent their pivotal point with the bracket 18, suitable operating rods 22 which have their lower ends pivotally connected to the links 23 which have their inner ends pivotally mounted in ears 24 upon the central sill 2. In normal position, the lower ends of the rods 22 rest upon bracket arms 25 carried by the truck so that when the car is tilted to one side, the rods 22 will rest upon the brackets and force the levers 19 upwardly thus raising one of the sides. After the load has been dumped the side thus raised acts as a counter-weight to return the body of the car to normal horizontal position. The fulcrum point of the levers 19 upon the rods 22 being arranged adjacent the brackets 18, a considerable leverage is obtained by the comparatively small weight of the sides 9.

It will be noticed that the sides are freely pivoted to the levers and are limited in their downward movement by the arms 21 so that when they are returned to operative position for closing the body, they will be properly guided into engagement with the fingers 12 and the extensions 14 will properly engage the apertured brackets 15.

Suitable chains are pivoted to opposite ends of the car adjacent each side and similar chains are pivoted to opposite ends of the truck at each side thereof, as shown at 26 and 27. Chains 27 carry the ordinary lever connectors which are adapted to connect with the chains 26 so as to hold the car in upright or load containing position. When the chains 26 and 27 at one side of the car are released that side of the car will be permitted to rise or tilt to the position shown in Fig. 3. This tilting of the car brings the links 23 and the raising rods 22 upon the brackets 25, thus producing a rigid support which when the car tilts, will raise the arms 19 and thus elevate the side 9.

Having thus described the invention, what is claimed is—

In a device of the kind described the combination of a dump car, said car having an open side, a door arranged to close the open side of said car, brackets mounted at right angles upon said door, each of said brackets being formed with an upwardly-inclined cam surface, a plurality of tenons carried by said door and having beveled ends projecting below said brackets, oppositely-arranged and outturned guides formed upon said car at its bottom against which are adapted to engage the cam surfaces of said

brackets to cause said door to contact with said car, a plurality of socket members carried by said car into which the beveled ends of said tenons are arranged to project as said bracket cam surfaces are guided within said guides, and means whereby said door is moved into engagement with said guides.

In testimony whereof I affix my signature in presence of two witnesses.

JOHN JAMES IRVIN.
